Henry A. Johnson.

UNITED STATES PATENT OFFICE.

HENRY A. JOHNSON, OF HINDSVILLE, ARKANSAS.

WATER-CONVEYER.

SPECIFICATION forming part of Letters Patent No. 628,487, dated July 4, 1899.

Application filed March 27, 1899. Serial No. 710,727. (No model.)

To all whom it may concern:

Be it known that I, HENRY A. JOHNSON, a citizen of the United States, residing at Hinds-ville, in the county of Madison and State of 5 Arkansas, have invented a new and useful Apparatus for Conveying Water in a Bucket from a Source of Supply to a Distant Station, of which the following is a specification.

Heretofore carrier-frames adapted to travel 10 on a cable and propelled by means of a winch and rope have been used for conveying buckets therewith; but such carriers are not adapted for conveying water over a hill intervening between the source of supply and the distant station where the water is to be used, as contemplated by my invention, that is adapted to be used on hilly ground as well as on a level surface.

My invention consists in the arrangement 20 and combination of parts, as hereinafter set forth, pointed out in my claims, and illustrated in the accompanying drawings, in which—

Figure 1 is a side elevation of the apparatus in position as required for practical use in conveying water over uneven ground. Fig. 2 is a perspective view of a frame fixed to the post at the top of the hill over which the carrier to which a bucket is suspended must pass 30 back and forth upon the double inclined plane produced by a fixed track that extends from the point of supply to the point where the water is delivered. Fig. 3 is a perspective view of the carrier adapted to travel upon the double inclined track and to deliver water in 35 a bucket from one end of the track to the other. Fig. 4 shows a plan view of the arrangement of the operative parts as required to elevate the carrier and bucket by means 40 of the winch and rope after the bucket is emptied and is to be returned to the other end of the track to be refilled.

The letter A designates a double inclined plane and track formed of a cable or rod fixed 45 to suitable supports B and C at its ends and stretched over a suitable frame D, that is fixed to a post F, located in a central position relative to the supports B and C, to which the ends of the track A are adjustably connected.

A winch H is located at the station and end 50 of the track A, where the water is to be de-

livered, and a rope J fixed to the drum of the winch and extended between two pulleys k and k', mounted in the top of the frame D. 55 The rope is passed under the pulley k and over the pulley k' and from thence extended and connected with the carrier-frame adapted to travel on the track A as required to carry a bucket back and forth from the source of 60 water-supply to the station where the water is to be used.

L and L² are the uprights of the carrier-frame, connected at their lower ends by a cross-bar L³. The upper end portions of the 65 uprights are doubled downward and terminate in hooks m, that prevent the rope from sagging, and between the doubled portions are mounted pulleys (not shown) adapted to travel on the track A, as required to suspend 70 and operate the bucket-carrier on the double inclined plane of the track. A hook P is pivotally and adjustably connected with the cross-bar L³ of the carrier-frame in such a manner that a bucket R can be readily detachably connected with the hook to be suspended 75 therefrom and carried thereby in a perpendicular position while the carrier moves up and down over the double inclined plane and track A.

For adjustably connecting the rope J with the carrier-frame, as required to move the carrier in opposite directions, by means of the winch H, upward alternately on each side of the apex of the track A, a bar s is fixed to 85 the uprights L and L² of the carrier and one end of the bar provided with a lateral projection s', to which the end of the rope is fastened and the other end of the bar bifurcated 90 to admit the rope to be detachably connected therewith by simply placing it between the forks of that end.

In the practical use of my invention when a bucket of water is hung to the hook P of the carrier at the source of water-supply a 95 person at the station where the water is to be delivered can by operating the winch draw the carrier up the inclined plane on the track A far enough so that the carrier-frame will tilt as it passes over the apex and then descend to the person at the winch by force of gravity, as the rope J is allowed to uncoil 100 from the drum of the winch by the operator, who retains hold of the handle of the winch to

regulate the speed of the downward movement of the carrier and bucket suspended therefrom. When the bucket is emptied and replaced on the hook P of the carrier, and the 5 rope J, fastened to the projection s' of the fixed bars on the carrier, is doubled back over the pulley k at the apex of the track A and slipped into the bifurcated end of the bar s, so that in winding the rope upon the drum of the winch 10 the force will be applied to the said bar s of the carrier-frame, as required to draw the carrier-frame and bucket suspended therefrom up the inclined track and over the apex of the track far enough, the carrier-frame will 15 tilt over the apex and descend to the source of water-supply by force of gravity, as restricted in speed by the operator who has hold of the handle of the winch to govern the descent of the carrier and empty bucket to be 20 filled again.

It is obvious water can be thus advantageously carried varying distances and over elevations of various heights as well as over a level surface by means of my invention.

25 From the description of the construction and function of each part of the apparatus their coöperation and the utility of my invention will be readily understood; and

What I therefore claim as new, and desire 30 to secure by Letters Patent therefor, is—

1. In an apparatus for carrying water, a single double inclined track having stationary supports at its ends and a support at its apex consisting of a frame attached to a fixed 35 post and provided with two pulleys in the same horizontal plane at some space apart for directing a rope in the manner set forth for the purposes stated.

2. In an apparatus for carrying water in a 40 bucket, a carrier-frame consisting of two uprights rigidly connected by a cross-bar at their lower ends and their upper ends doubled downward and pulleys mounted in said double portions and a straight bar having a lat-

eral projection at one end for attaching a 45 rope thereto, and its other end bifurcated, fixed to the doubled portions of the uprights and a hook pivoted to the cross-bar, in combination with a double inclined track and means for operating the carrier-frame on the 50 track for the purposes stated.

3. An apparatus for conveying water, comprising a cable or rod fixed at its ends to stationary supports on the surface of the ground and connected at its center with a frame fixed to a post to produce a double inclined track 55 for a bucket-carrier to travel back and forth over the apex of the track, pulleys in the frame that supports the track at its apex for directing a rope, a carrier-frame having pulleys mounted therein to engage the track and a bar having a lateral projection at one end for attaching a rope thereto and bifurcated at its other end to admit a rope, a winch located at one end of the track, a rope connected with the winch and extended between the pulleys in the frame at the apex of the track and connected with a lateral projection on the bar of the carrier-frame, all arranged and combined to operate in the manner set 60 forth for the purposes stated.

4. The apparatus for conveying water in a bucket consisting of the double inclined track A, the end supports B and C, the frame D having pulleys k and k' on a fixed post F, a 75 winch H, a rope J connected with the winch and a carrier composed of the uprights L, L² cross-bar L³ and a bar s having a lateral projection at one end and bifurcated at its other end, two pulleys n mounted in the frame, a 80 hook P pivoted to the cross-bar at the bottom of the carrier-frame and a bucket R, all arranged and combined to operate in the manner set forth.

HENRY A. JOHNSON.
